UNITED STATES PATENT OFFICE.

WELLINGTON LOUGHEED, OF WYANDOTTE, MICHIGAN, ASSIGNOR OF ONE-HALF TO
JACOB B. SPARKS, OF ROYAL OAK, MICHIGAN.

DOOR-LOCK.

1,352,819.

Specification of Letters Patent. Patented Sept. 14, 1920.

Application filed August 11, 1919. Serial No. 316,712.

To all whom it may concern:

Be it known that I, WELLINGTON LOUGHEED, a citizen of the United States, residing at Wyandotte, county of Wayne, State 5 of Michigan, have invented a certain new and useful Improvement in Door-Locks, and declare the following to be a full, clear, and exact description of the same, such as will enable others skilled in the art to which it 10 pertains to make and use the same, reference being had to the accompanying drawings, which form a part of this specification.

This invention relates to door latches, and an object thereof is to provide a door latch 5 in which the spring protracted latch bolt may be utilized as a locking member normally adapted to be retracted by the door knob on the inside of the door and prevented from operation by the knob on the 10 exterior of the door. A further object of the invention is to provide a lock or latch of the character stated with means for setting the mechanism whereby the latch may be freely operated by either knob. An additional object of the invention is to provide a latch of the character stated with means for holding the latch from operation by the exterior knob and a spring-projected member capable of being set to hold the 15 latch locking member out of engagement with the latch or to permit its engagement therewith. A further feature of the invention is involved in the mechanism for automatically releasing the locking member from the latch by the turning of one of the knobs. These and other objects and the several 20 novel features of the invention are herein-after more fully described and claimed and the preferred form of construction involving the invention is shown in the accompanying drawings in which—

Figure 1 is a view of the outside of the lock case.

Fig. 2 is a view of the case with the cover 5 removed showing the latch locking mechanism.

Fig. 3 is a similar view showing the position assumed by the parts on turning the interior door knob.

Fig. 4 is a similar view showing the locking member retained in position to permit operation of the latch member by either door knob.

Fig. 5 is a latch member as operated by 5 the exterior door knob.

Fig. 6 is a section taken through the latch case on line 6—6 of Fig. 3 showing the two door knobs and part of the latching bolt.

Fig. 7 is a perspective view of the latch locking member. 60

Fig. 8 is a perspective view of the latch locking member.

Fig. 9 is a perspective view of the locking member operating pawl.

Fig. 10 is a detail showing the relationship of the locking member operating pawl and operating hub of the interior door knob. 65

Fig. 11 is a detail in perspective of the key for operating the locking member pawl from the exterior. 70

Fig. 12 is an enlarged section taken on line 12—12 of Fig. 4.

In its preferred form the lock consists of the usual casing 1 inclosing the several parts and a latch member or bolt 2 having a 75 beveled face 3 as is usual with spring-retracted latches. The latch member is normally forced outward by a spring 4 engaging in notches 61 and 62 in the latch member shown in Fig. 7, but it is to be understood that the spring may be applied to the latch member in any desired manner. The latch member is provided with two rearwardly extending arms 5 and 6 as shown, the ends of which are inturned providing 80 lugs 7 and 8 for each arm respectively against the inner faces of which the lugs 9 and 10 of a hub 11 may engage as shown in Figs. 2 and 4. The hub 11 is secured to a square shaft 12 on which is mounted the 85 knob 13 on the outside of the door as shown more particularly in Fig. 6. The arms 5 and 6 of the latch member are recessed from the point of union at the forward end to the rear ends thereof which provides shoulders 90 15 and 16 and lying in these recesses is a locking bar 17 extending laterally of the case. This locking bar 17 is guided by a bearing 18 as shown in Fig. 2 and lugs 19 and 20 and 20^a on opposite sides thereof 95 between which the locking bar 17 is reciprocal. The locking bar 17 is provided with extensions or arms 21 and 22 thereon extending in the plane of the locking bar and adapted for engagement against the shoulders 15 and 16 of the latch members respectively as shown in Fig. 2. A spring 23 tends to hold the locking bar in the position shown in Fig. 2 with the arms 21 and 22 engaging against the shoulders 15 and 100 105

22 engaging against the shoulders 15 and 110

16 of the latch member in which position the latch member is held from being retracted by the outer door knob and the hub 11 on the shaft thereof. It is to be noted that 5 when the bar 17 is in this locking position shown in Fig. 2, a squared part 24 of the hub 11 engages against the flat side of the bar 17 and this also tends to prevent rotation of the knob. On movement of the bar 10 17 from the position shown in Fig. 2 to that shown in Fig. 3, the recessed or cut out portion 25 of the locking bar 17 is brought to position adjacent this flat portion 24 of the hub 11 so that in the position of parts shown 15 in Fig. 3 the hub may be turned and the latch operated after the manner as indicated in Fig. 5.

The locking bar may be forced to this position shown in Fig. 3 or 5 by the knob 26 20 on the inside of the door secured to the inner end of the shaft 27 on which is secured a hub 28 similar in all general respects to the hub 11 of the outer door knob. This hub 28 is shown in Fig. 10 and has lugs 29 and 25 30 thereon for engaging the lugs 7 and 8 of the latch member. The lug 29 of the hub 28, however, does not bear directly against the lug 7 of the latch member but against an arm 31 of the pivoted pawl 32 on the 30 inner face of the casing shown in detail in Fig. 9. This pawl has a pin 34 which fits an aperture in the casing as will be understood and is provided with an arm 35 which engages against an enlarged portion 36 at 35 the end of the locking bar 17 shown more particularly in Fig. 8. By reason of the lug or arm 29 engaging against the arm 31 of the pawl, rotation of the knob 26 in one direction to the right of Fig. 10 turns the 40 pawl on its axis forcing the locking bar laterally of the case to unlocking position shown in Fig. 3 with the arms 21 and 22 of the locking bar out of contact with the shoulders 15 and 16 of the arms of the latch 45 member permitting the latch to be retracted against the tension of its spring. Under normal conditions the release of the knob member permits the latch member to again be projected by its spring and the spring 50 23 returns the locking bar to its normal position shown in Fig. 2. Thus with the arrangement described, the latch may be operated freely from the interior of the door and is locked from operation from the exterior. To unlock the device from the exterior I have preferably provided a key 40 shown in Fig. 11 having a semi-circular end 41 terminating in two pin like arms 42. The case is provided with a semi-circular slot 43 permitting the introduction of the key and the pawl 32 is provided with apertures 44 for the pin ends 42 of the key so that rotation of the key in one direction turns the pawl and, by reason of the engagement of the arm 35 with the enlarged por-

tion 36 of the locking bar and of the arm 31 with the lug 7 of the latch member, rotation of the pawl releases the locking bar and retracts the latch member. It is to be noted particularly from Fig. 2 that the shoulders 70 15 and 16 are formed at an angle to the lateral axis of the lock case and rotation of the pawl 32 retracts the latch member 2 at the same time moving the locking bar 17 downward the angular shoulders 15 and 75 16 of the latch 2 allowing downward movement of the locking bar and arms 21 and 22 while the latch 2 is being retracted.

The lock may be manufactured as described above in which case it is only possible to operate the latch with the knob from the inner side and with a key from the outer side and the principal features of the invention are involved in this described construction. It is, however, often 80 times desirable to provide a latch which is operable only from one side and at the other times to so set the lock and mechanism that it may be freely operated from either side. For this purpose I have provided what I have here termed a retainer 85 slidingly and swingingly supported between the lock case and the escutcheon. This consists of a flat bar 50 which extends through a slot 51 in the case and through the escutcheon as shown in Fig. 12. A pin 52 is provided in the bar 50 which is positioned in a slot 53 shown in dotted lines in the door between the lock case and the escutcheon permitting a longitudinal movement of the bar 50 in the case. The bar 50 is positioned below the angular end 59 of the locking bar 17 so that on downward movement of the bar 17 and angular end the bar 50 is engaged and swung on the 90 pivot pin 52 to the right of the position shown in Fig. 2 and against the tension of the spring 55 until the notch 56 in the locking bar registers with the bar 50 at which time the spring 56 forces the bar 50 into the 95 notch 56, and thus holds the locking bar in unlocked position shown in Fig. 3 in which position both the inner and the outer knob may be used to actuate the latch and under the conditions stated the locking bar will 100 be held out of its locking relation with the latch member for an indefinite period. The lock member, however, may be released at any time simply by retracting the bar 50 and pin 52 the length of the slot 53 until 105 the notch 54 in the bar 50 registers with the notch 56 of the locking bar releasing the locking bar to action by the spring 23 which draws the same to locking position shown in Fig. 2 under which condition the 110 bar 17 is never engaged by the bar 50 due to the fact that the notch 54 in the bar 50 permits movement of the locking bar 17 without resulting in engagement of the 115 parts.

As before stated, the lock or latch device may be manufactured either with or without this pivoted bar 50 but I prefer to use this bar 50 for the purposes herein specified.

Having thus briefly described my invention, its utility and mode of operation, what I claim and desire to secure by Letters Patent of the United States is—

1. In a door lock, a member operable by an interior door knob, a member operable by an exterior door knob, a latch member actuated by the interior door knob, a locking bar holding the latch member from movement, means for disengaging the locking bar from the latch member by operation of the interior door knob, and means for holding the locking bar in disengaged position to allow operation of the lock by both door knobs.

2. In a door lock, an interior and an exterior door knob, a separate shaft for each knob, a hub on each shaft, lugs on the said hubs, a latch member engaged by the said lugs and a locking bar normally holding the latch from movement, and means whereby, upon rotation of the interior door knob and shaft, the locking bar is first disengaged from the latch member and the latch member is then retracted.

3. In a door lock, a member operable by an interior door knob, a member operable by an exterior door knob, a latch member operable by both door knobs, a spring-actuated locking bar normally held in engagement with the latch member allowing operation of the lock by the interior door knob and preventing operation of the lock

by the exterior door knob, and means for releasing and holding the locking bar from engagement with the latch member to allow operation of the lock by the exterior door knob.

4. In a door lock, a member operable by an interior door knob, a member operable by an exterior door knob, a latch member having arms extending therefrom, lugs on the said arms engaged by the said members operable by the door knobs, a locking bar normally holding the latch member from movement, a pawl engaging the locking bar and rotatable by the interior door knob whereby the pawl is rotated to disengage the locking bar from the latch member, and a catch adapted to hold the locking bar in disengaged position permitting operation of the lock by either knob.

5. In a door lock, a door knob, a latch member having two rearwardly extending arms, lugs on the ends of the said arms, a member engaging said lugs rotatable by the door knob and adapted to retract the latch member upon rotation of the door knob, shoulders on the said latch member, a locking bar normally engaging thereagainst preventing movement of the latch member, and a pawl rotatable upon rotation of the door knob and adapted upon rotation thereof to disengage the locking bar from the latch member thereby allowing the latch member to be retracted.

In testimony whereof, I sign this specification.

WELLINGTON LOUGHEED.
